[57] CLAIM

The ornamental design for a table base, as shown and described.

DESCRIPTION

FIG. 1 is a top front and left side perspective view of a table base showing my new design;

FIG. 2 is a side elevational view thereof the opposite side being identical thereto;

FIG. 3 is a front elevational view thereof;

FIG. 4 is a side elevational view, taken along line 4—4 in FIG. 3;

FIG. 5 is a top plan view; and,

FIG. 6 is a bottom plan view thereof.

The table top shown in broken lines is not part of the design sought to be patented.
